UNITED STATES PATENT OFFICE.

JOHN GASPER, OF CLAYVILLE, NEW YORK.

DESIGN FOR A BOOT.

60,133.

Specification for Design.

Patented Jan. 3, 1922.

Application filed March 17, 1921. Serial No. 453,155. Term of patent 7 years.

To all whom it may concern:

Be it known that I, JOHN GASPER, a citizen of Czecho-Slovakia, residing at Clayville, in the county of Oneida and State of New York, have invented a new, original, and ornamental Design for a Boot, of which the following is a specification, reference being had to the accompanying drawing, forming part thereof.

The figure is a view in perspective of a boot, showing my new design.

I claim:—

The ornamental design for a boot, as shown.

JOHN GASPER.
